DES. 2027

Confined to and George A. Wickcox, of Brooklyn, N.Y.

inventor June 14th 1874. Letters Patent No. 12037 Dated Jan'y 21-1865.

2 M. Patent in Design for a Revolving Pistol Handle.

The schedule referred to in these Letters Patent and making part of the same.

Is all whom it may concern:

Be it known that I, George A. Wickcox, of Brooklyn, in the County of Kings and State of New York, have invented and made a certain new and original Design for the shape of the Handle of a Revolving Pistol, and do hereby declare the following to be a full, clear and exact description of the same, reference being had to the accompanying photographic drawing of the same.

The nature of the said design consists in the curved, rounded handle as adapted to set within the hand and extended to receive the cylinder of the revolver as at b, and the trigger as at c.

This shape is neat and handsome in appearance and there are no sharp projections to interfere with the grasping of the handle or its insertion in, or withdrawal from, the pocket or case receiving the same when not in use.

It will be apparent from the photograph that the entire handle is a series of curves both longitudinally and at any point transversely of said handle, as represented.

DES. 2027

2

What I claim and desire to secure by Letters Patent is
The Design of the ornamental curved shape or configuration
of the handle applied to a revolving pistol, as represented

Dated this 19th day of April A.D. 1864.
